JENNINGS GRANT AMBROSE AND HENRY W. AMBROSE, OF LOMA PORTAL, CALIFORNIA.

SPARK-PLUG.

1,319,133.

Specification of Letters Patent.

Patented Oct. 21, 1919.

Substitute for application Serial No. 108,690, filed July 11, 1916. This application filed December 10, 1918. Serial No. 286,087.

To all whom it may concern:

Be it known that we, JENNINGS GRANT AMBROSE and HENRY W. AMBROSE, citizens of the United States, residing at Loma Portal, in the county of San Diego, State of California, have invented a new and useful Spark-Plug, of which the following is a specification.

The device forming the subject matter of this application is a spark plug, and one object of the invention is to provide a device of this type in which the thimble which carries the porcelain body of the plug is spaced from the casing portion of the plug to define an air chamber which prevents excessive heating and a breaking of the porcelain body, combined with means whereby moisture or water will be prevented from entering the chamber.

Another object of the invention is to provide a spark plug in which the electrodes cooperate in a novel manner.

It is within the province of the disclosure to improve generally and to enhance the utility of devices of that type to which the present invention appertains.

With the above and other objects in view, which will appear as the description proceeds, the invention resides in the combination and arrangement of parts, and in the details of construction hereinafter described and claimed, it being understood that changes in the precise embodiment of the invention herein disclosed can be made, within the scope of what is claimed, without departing from the spirit of the invention.

In the accompanying drawings:—

Figure 1 is a longitudinal section showing a spark plug constructed in accordance with the invention; Fig. 2 is a side elevation of the plug; Fig. 3 is an end elevation of the plug; Fig. 4 is a cross section on the line 4—4 of Fig. 1.

In carrying out the present invention, there is provided an outer casing 9, which, preferably, is made of metal. The casing 9 is externally screw-threaded as shown at 10, so that it may be mounted in the head of an internal combustion engine, or be otherwise located at the proper point, the casing 9 including a wrench head 7, whereby the casing may be rotated readily. The casing 9 has an enlarged upper bore 11 which is outwardly flared at its upper end as shown at 12, the casing including a smaller lower bore 14, the

bore 11 and 14 co-operating to define an internal shoulder 15 in the casing. Below the shoulder 15, the casing 9 is internally threaded as shown at 16. The upper end of the casing 9 is downwardly and outwardly beveled as shown at 17. In the casing 9, near to its lower end, openings 18 are formed. Screws 8 are threaded into the lower end of the casing 9, the screws 8 constituting electrodes. The screws 8 are all of the same length, but the openings in the casing 9 which receive the heads of the screws are countersunk to different depths so that one screw 8 projects inwardly to a less distance than a second screw, the second screw projecting inwardly a less distance than a third screw. Any desired number of screws or electrodes 8 may be provided. The lower end of the casing 9 is cut away as shown at 19.

The numeral 20 denotes a thimble which, preferably, is made of metal. The lower end of the thimble 20, indicated by the reference character 21, is of less diameter than the body portion of the thimble and is threaded into the part 16 of the casing 9. Since the lower end 21 of the thimble 20 is of smaller diameter than the body portion of the thimble, there is formed a shoulder 22 which abuts against the shoulder 15 of the casing. The thimble 20 is provided with an enlarged wrench head 23, spaced from the upper end of the casing 9, and undercut as shown at 24, the wrench head 23 including a conical apex 5, having an internal shoulder 25. At this point it should be observed that the outer surface of the thimble 20 is spaced from the inner surface of the enlarged upper bore 11 of the casing 9, so as to define an air chamber 26, the space between the wrench head 23 of the thimble 20 and the upper end of the casing 9 constituting an inlet 6 for the air chamber 26.

The numeral 4 denotes a body made out of porcelain or other suitable insulating material, the body being received in the thimble 20. Adjacent its upper end, the body 4 is reduced in diameter to form a shoulder 27 which abuts against the shoulder 25 of the thimble 20. The body 4 projects upwardly above the part 5 of the thimble 20, and is provided with an axial bore 28, enlarged intermediate its ends, and adjacent the upper end of the body 4, to form a recess 29.

In the bore 28 of the body 4 is located a

metal electrode 3, the lower end 34 of which is fashioned from some material which will not deteriorate readily under the action of a spark, the end 34 of the electrode 3 projecting downwardly below the lower end of the body 4. Intermediate its ends, the electrode 3 is provided with an enlargement 30, fitting closely in the recess 29 of the body 4. The upper end of the electrode 3 projects beyond the upper end of the body 4 and is threaded as shown at 31. Surrounding the threaded end 31 of the electrode 3 and resting on the upper end of the body 4 is a metal washer 32.

15 The numeral 2 denotes a metal tip which, preferably, is of conical form, the tip 2 having an axial recess 33 which receives the threaded end 31 of the electrode 3. The tip 2 has a wrench head 35 whereby it may be rotated readily. In the tip 2, near to its upper end, is formed a cross opening 36, communicating with an axial opening 37 into which a metal binding screw 38 is threaded.

25 Because the thimble 20 is spaced from the casing 9 to form the air chamber 26, an excessive heating of the porcelain body 4 is avoided, and a breaking of this element will be prevented. Since the upper end of the 30 casing 9 is downwardly and outwardly beveled as shown at 17, and since the bore 11 of the casing is flared as shown at 12, air can enter the chamber 26 readily, through the inlet 6. It is to be observed that the 35 wrench head 23 of the thimble 20 projects outwardly beyond the upper end of the air chamber 26, and, consequently, moisture is prevented from entering the air chamber. Moisture is prevented from entering the air 40 chamber 26, further, because the wrench head 23 is undercut as shown at 24, and because the upper end of the casing 9 is downwardly and outwardly beveled as shown at 17. Thus, although air can enter and leave 45 the chamber 26 readily, thereby cooling the body 4, it will be difficult for moisture or water to enter the air chamber.

Especial attention is directed to the fact that the screws or electrodes 8 are spaced at 50 different distances from the lower end 34 of the electrode 3. The screws 8 are made of some material which will not deteriorate readily, due to the action of a spark. If, however, that screw 8 which approaches 55 nearest to the lower end 34 of the electrode 3 should deteriorate, then the screw 8 which approaches the lower end 34 of the electrode next closely will become operative, and when 60 this last-specified screw or electrode becomes inoperative, then the third screw or electrode 8 will exercise its obvious function. A spark thus is at all times assured. As has been stated hereinbefore, the screws 8 are all 65 of the same length, although their heads are countersunk at different distances into the

lower end of the casing 9. As a consequence, the operator, or a manufacturer, does not have to carry in stock, three different lengths of screws, and confusion resulting from a failure to select a screw or electrode 8 of the proper length is avoided.

A conductor (not shown) may be inserted through the cross opening 36 in the tip 2, and be held in place by the binding screw 38. If desired, the conductor may be bound 75 between the tip 2 and the metal washer 32. Thus, two means for coupling up the conductor with the spark plug are provided.

Since the enlargement 30 of the electrode 3 is received in the recess 29 of the body 4, the electrode 3 cannot rotate or move endwise in the body 4. Noting that the shoulder 27 on the body 4 abuts against the shoulder 25 on the thimble 20, it will be understood that the body 4 cannot move outwardly, due to pressure created in the explosion chamber of the engine wherewith the spark plug is assembled.

The upper edges of the openings 18 in the lower end of the casing 8 are flush with the 90 lower end of the body 4. The openings 18 permit soot to escape and afford a means whereby a fresh charge of gas may enter readily about the co-operating electrode elements 8 and 34. The cutting away of the 95 lower end of the casing 9, indicated at 19, aids in preventing an obstruction of the entering gas. Since the upper edges of the openings 18 are flush with the lower end of the body 4, no recesses are formed in which 100 foul matter can collect.

Having thus described the invention, what is claimed is:—

1. A spark plug comprising a casing; a thimble in the casing, the inner end of the 105 thimble and the casing having detachably interengaged parts, the external wall of the thimble being spaced from the internal wall of the casing outwardly of said parts to define, about the thimble, an air chamber 110 which is open at its outer end, the thimble including an enlargement spaced from the outer end of the casing and extended laterally above the open end of the air chamber to serve as a guard therefor; a body within 115 the thimble and closely filling the same; and an electrode closely embraced by the body.

2. A spark plug comprising a casing; a thimble in the casing; a body in the thimble; and an electrode carried by the body, the 120 thimble being spaced from the casing to define an air chamber, and the thimble including an enlargement spaced from the end of the casing and extended outwardly above the air chamber to serve as a protection therefor, 125 the end of the casing being outwardly beveled.

3. A spark plug comprising a casing; a thimble in the casing; a body in the thimble; and an electrode carried by the body, the 130

thimble being spaced from the casing to define an air chamber, and the thimble including an enlargement spaced from the end of the casing and extended outwardly above the air chamber to serve as a protection therefor, the enlargement being undercut.

4. A spark plug comprising a casing; a thimble in the casing; a body in the thimble; and an electrode carried by the body, the thimble being spaced from the casing to define an air chamber, and the thimble including an enlargement spaced from the end of the casing and extended outwardly above the air chamber to serve as a protection therefor, said end of the casing being outwardly beveled, and the enlargement being undercut.

5. A spark plug comprising a casing; a

main electrode within the casing, and extended longitudinally of the casing; and secondary electrodes movably carried by the casing and disposed transversely of the casing, the inner ends of the secondary electrodes being spaced at different distances from the main electrode, all of the secondary electrodes being of the same length, the secondary electrodes being provided with heads, and the casing being provided with seats which receive the heads, the seats being of different depths.

In testimony that we claim the foregoing as our own, we have hereto affixed our signatures.

JENNINGS GRANT AMBROSE.
HENRY W. AMBROSE.
